UNITED STATES PATENT OFFICE

1,962,651

MACHINE FOR APPLYING WRAPPING MATERIALS TO CANISTERS

William Henry Wall, London, England, assignor
to A. Wander Limited, London, England, a
British Company

Application May 17, 1932, Serial No. 611,794
In Great Britain June 13, 1931

12 Claims. (Cl. 93—7)

This invention comprises improvements in automatic machines for wrapping canisters with paper or the like.

Hitherto it has been customary in the wrapping of canisters by hand, to wrap the sheet of paper or other material round the canister so as to form a cylinder of the paper encircling the canister and projecting at each end beyond the ends thereof, and then to fold over the projecting ends of the paper, pressing the folds flat against the ends of the canister.

A principal object of the present invention is to provide an automatic machine in which some of these operations are performed mechanically.

It has been found that when folding in the projecting ends of the wrapper on a cylindrical canister, particularly one of a diameter such as two inches or more, in a series of overlapping folds, neat and correct folds cannot be formed unless sharp and definite creases are first formed. When a part of the wrapper is folded in to form one fold, outstanding parts remain, and the wrapper becomes doubled on itself. It is along the line where the doubling takes place that it is desirable to form a sharp and definite crease. Accordingly, it is a further object of the invention to provide an automatic machine having means for folding in the projecting ends of a wrapper of greater width than the length of a canister which it encircles, in a series of overlapping folds, means for creasing the parts of the wrapper where it becomes doubled upon itself as a result of the folding in of one fold and means for folding in the thus creased parts to form a fold or folds overlapping previously folded in folds.

According to a feature of the invention, the aforesaid means for folding over the projecting ends of the wrapping sheet encircling the partially wrapped canister may comprise a step-by-step conveyor for moving the canisters in succession past a series of folding stations, the canisters pausing momentarily opposite each station, and at each station a finger or set of fingers which are reciprocable towards and away from the partly wrapped canister in position at the station and are adapted to press a portion of the said projecting end of the wrapper into a fold against or to lie against the end of the canister, the finger or sets of fingers at the several stations being arranged to operate upon different portions of the projecting end of the wrapper.

Conveniently, the two projecting ends of the

wrapper may be folded simultaneously, in which event, there would be at each folding station, a pair of fingers or sets of fingers operable simultaneously upon the wrapper.

According to another feature of the invention there may be provided in the machine, a step or steps in advance of the folding stations in the path of the canisters, a plunger situated at the side of said path and having a pad at the end, adapted when the plunger is moved towards a canister in position at the station to flatten the folds of the wrapper firmly against the end of the canister.

Conveniently, as in the case of the folding operations, the flattening of the folds of the wrapper may take place at both ends of the canister simultaneously, in which event, the machine would comprise a pair of flattening plungers opposed to one another, and situated one on either side of the path of the canisters.

A further feature of the invention comprises the provision in the machine, a step or steps in rear of the folding stations and situated one on either side of the path of the canisters on the conveyor, of a pair of opposed canister-aligning plungers reciprocable in time with the movements of the conveyor in such a manner as, during the dwell periods in the movement of the conveyor, to enter the open ends of the wrapper encircling the canister in position opposite the plungers, and, if the canister is not already in alignment with the folding stations, to shift it within the wrapper into alignment therewith.

It is to be understood that the two portions of the machine which function, respectively (a) partially to wrap the canister by encircling it with a sheet of wrapping material (with or without the insertion between said sheet and the canister of a pamphlet, coupon, card or the like), and (b) to fold over the projecting ends of the encircling sheet towards the ends of the canister and press the folded-over ends in stiff creases against the ends of the canisters, may either be brought together in one single machine, or, if desired, may comprise separate units, the partially wrapped canisters, in this event, being passed from the first unit to the second either by hand or by means of a conveyor.

One practical embodiment of the invention will now be described by way of example. In this embodiment, the two foregoing parts of the machine (a) and (b) comprise separate units which will be referred to respectively, as the wrapping unit and the folding unit.

In the drawings:—

Figure 1 is a side elevation of part (a) of the machine, namely the wrapping unit.

Figures 2a and 2b represent side elevations 5 of the end-folding unit shown in two parts.

Figures 3a and 3b represent an end elevation 10 of the same.

Figures 4 and 5 are two views in perspective 15 of a wrapped canister showing the opposite ends thereof respectively and indicating the character of the folds made by the end-folding unit.

Figures 6 and 7 are details of centering apparatus in the first station of the end-folding machine.

Figures 8, 9 and 10 are details of the apparatus 15 of the second station where the first fold is made.

Figure 11 is a detail of the apparatus of the third station.

Figures 12, 13 and 14 are details of the apparatus 20 at the fourth station.

Figures 15 and 16 are details of the apparatus of the fifth station.

Figures 17 and 18 are details of the apparatus 25 of the sixth station.

Figures 19 and 20 are details of the apparatus of the seventh station.

Figures 21, 22 and 23 are details of the apparatus of the eighth station.

Figures 24, 25 and 26 are details of the apparatus 30 of the ninth station.

Figures 27 and 28 are details of the apparatus of the tenth station.

Figure 29 is a perspective view of the eleventh 35 station, and

Figure 30 is a plan of a part of the machine showing an alternative construction.

The wrapping unit comprises an elongated horizontal table 10 (Figure 1) above which are 40 mounted a pair of rails 11 parallel to one another and extending in the direction of the length of the table from a point near one end thereof to a point near the centre of the table.

This unit is more fully described in my co-pending patent application of even date here-with, Serial No. 611,793, but the following description will serve to make clear the main features of the machine, some of which are hereinafter referred to in the appended claims.

Canisters 12 are fed from a chute 14 on to the rails 11 through automatic releasing mechanism which comprises two detents 15, 16 pivoted at 17, 18 and automatically and alternately raised by means of cams 19 so that the canisters 55 are allowed to pass them one at a time. The canisters are rolled along the rails 11 by means of an endless band or belt 20 which overlies the canisters and moves parallel to the rails 11. A gluing or cementing roller or wheel 21 is mounted on a pivot 22 above a vessel 23 which contains glue or other cement, so that the periphery of the gluing roller dips into the cement. The upper edge of the gluing roller 21 lies slightly above the level of the rails 11 and 60 touches the periphery of the canisters 12 as they pass over it, thus depositing a narrow strip of the glue or other cement upon the periphery of the canister at or near the extreme ends thereof. The belt 20 is arranged to 65 engage the canister at the place between the rails 11, while the gluing wheels 21 engage it outside the rails 11, and thus the belt is clear of the cemented portion of the canister which is kept from being made sticky thereby. At 70 the ends of the rails 11 there is a downward

ramp or slope 28 which serves to deliver the canisters on to the top of a pile 26 of wrappers accommodated within a vertical open top magazine 27. The canister 12 having been deposited upon the rails 11 on the top wrapper of the pile 26 is rolled across the same by the friction belt 20. The proportions of the apparatus are such that the glued portion of the edge of the canister contacts with the edge of the wrapper 26 with which it first comes into contact and thus picks up this edge of the wrapper and in rolling forward rolls the wrapper around itself. Rollers 24, 25 which engage the belt 20 serve to keep it at the proper distance above the rails 11 and the pile of wrappers 26 during these operations.

If desired pamphlets 30 from a magazine 31 may be laid one by one upon the pile of wrappers 26 by means of an automatic withdrawal plunger 32 so that each canister has wrapped around it within the wrapper 26 one of the pamphlets. The withdrawal plunger 32 draws the pamphlets from the bottom of the magazine 31 and the detail of the operation of this mechanism and of other parts of the machine shown in Figure 100 1 is more fully described in co-pending patent application Serial No. 611,793 of even date here-with. It will be sufficient to point out herein that the plunger 32, which is viewed endwise in Figure 1, is reciprocated above the pile of 105 wrappers 26 and that it carries a movable finger or gripper for engaging the pamphlets, having a roller 47, and a trip finger 46 lies in the path of the said roller so that the pamphlets are automatically deposited upon the pile. The 110 plunger 32 is operated from a rockshaft 75 through a lever which is connected by a link 53 to a cam for operating it, which cam is located upon a shaft 74 extending parallel to the bed 10 and upon the side of the machine 115 which is remote from the point of observation in Figure 1. The shaft 74 is operated through a friction clutch and gearing which in itself forms no part of the present invention.

Near the left-hand side of the pile of wrappers 120 is a transverse gluing band 66 which runs over rollers and the underside of which closely overlies the pile of wrappers 26. At one end of its travel the gluing band passes over and dips into a glue or cement pot 67. The effect 125 of this band is to apply a line of glue to the left-hand edge of the wrappers as more fully described in the aforesaid co-pending patent application, and the canisters, after rolling the wrapper completely around themselves pass 130 over the unglued upper side of the lower length of the gluing band 66, drawing the trailing edge of the wrapper out from underneath the gluing band and causing it to adhere to the side of the wrapper which was first attached 135 to the canister. The wrapper is thereby glued to itself and the canisters pass on along the shelf 69 to a conveyor 93 at the exit to the machine. The conveyor 93 is supported by a standard 94 and is driven by a sprocket 95 through 140 gearing 96, 97 which is operated by a bevel gear on the end of the shaft 74 aforesaid.

In addition to the mechanism above described there is means for lifting a table 72 which supports the underside of the pile of wrappers 26 145 and thus for keeping the uppermost wrapper always at a constant level notwithstanding the continual removal of wrappers therefrom in the operation of the machine.

To this end the table 72 is supported upon a 150

vertical rack 87 which can be raised and lowered by means of a pinion 89 on a shaft extending transversely to the machine below the bed 10. The shaft which carries the pinion 89 carries 5 also a hand wheel 88 and a sprocket to mesh with a chain 91, which chain passes over pulleys to a counterweight 90. Thus the table 72 is continuously but yieldingly urged upwards. In addition to this mechanism there is a vertical 10 rack 76 connected with the table 72 and the rack 76 meshes with the pinion 77 fast with the spur gear 78 which meshes with the pinion 79 fast to a gear 80. The gear 80 meshes with a pinion 81 on the same spindle as a ratchet wheel 82. 15 Thus, the rack is operated through a compound reduction train from the ratchet wheel 82. With the ratchet wheel 82 there engages a pawl 85 pivoted on a bracket secured to the underside of the bed 10 and this pawl holds the table 72 20 positively from downward movement. In addition there is a reciprocable pawl 84 connected by a link 83 with an arm on the rockshaft 75 which operates the plunger 32. Thus, every occasion 25 on which the plunger 32 withdraws a pamphlet from the mechanism 31 and lays it upon the pile of wrappers 26 is accompanied by a movement of the pawl 84 which lifts the table 72 and raises the pile of wrappers thereon. The compound 30 train of gearing 76 to 82 is made of such ratio as to render this movement equivalent to the thickness of one wrapper, and therefore the top of the pile of wrappers 26 is kept in a constant position.

The partly wrapped canister, having been 35 rolled along the horizontal shelf 69 by the friction band 20, is delivered to a conveyor 93 supported on a standard 94 and driven by a roller 95 through pinions 96, 97. The pinion 97 is fast with a bevel gear which meshes with a co-operating bevel gear on the drive shaft 74 of the machine. The conveyor serves to deliver the canisters to the folding unit of the machine which will now be described.

The folding unit which is shown in its general 40 arrangement in Figures 2a and 2b comprises a bed plate 100 supported on standards 101, 102 and extended at the entering end of the machine beyond the standard 101 over a third standard 103. The extended portion 104 of the bed plate constitutes a convenient table where the canisters may be placed in position for operation 45 by the machine. There is a drive shaft 105 which is actuated by a reduction gear 107, 108 from a shaft 109 which carries a belt pulley 110. The belt pulley 110 is loose upon the shaft but contains a friction clutch 111 operated by a push rod 112 from a hand lever 113. Some of these parts are best seen in Figures 3a and 3b 50 of the drawings. Upon the end of the shaft 109 is a large hand wheel 114 by which the machine may be adjusted or tried by hand prior to applying power if desired.

Extending below the bed plate 110 along the 55 whole length of the machine there are two longitudinal cam shafts 115, 116 by which the various folding mechanisms are operated. The bed plate 100 is in two parts as best seen in Figure 3 with a longitudinal channel between them throughout the length of the machine. In the central longitudinal channel of the bed plate there slide a number of carriers 117 in the form of bronze castings having upstanding horns at each end shaped to receive the canisters. The carriers are secured upon a pair of chains 118, 119 which run over a small pair of idle sprockets 120 at the entering end of the machine above the standard 103 and a large pair of driving sprockets 124 at the other end of the machine. The idle sprockets 120 are mounted upon a shaft 121 carried in slideable bearings 122 which are capable of adjustment by means of screws 123 to take up slack in the chain. The driving sprockets 124 are mounted on a shaft 125 which carries at one end a five-armed star driving element 126 of well known type to co-operate with the rotating crank pin 127 on a shaft 128. The shaft 128 carries a spur wheel 129 which meshes with a second spur wheel 130 upon a cross-shaft 131 driven by a bevel gear from the shaft 115. Thus the carriers 117 are advanced 60 intermittently by the star wheel drive 126 and the amount of the advance movement at each rotation of the crank pin 127 is made to correspond with the pitch of the carriers 117 upon the chain. Moreover, the various mechanisms which perform successive operations upon the canisters are all located at a similar pitch distance apart from one another and they are timed by the cams upon the shafts 115, 116 to operate during the periods when the chain 118 is at rest, 65 and to be free from engagement with the canisters during the time when the said chain is in movement. Thus, in the course of their passage through the machine the canisters come successively to rest at a number of operating stations, 70 and a single operation is performed upon each canister at each station by the mechanism, the whole series of operations resulting in completely folding in the paper wrapper at both ends of the canister and delivering it in finished condition 75 at the outlet of the machine. There are eleven stations altogether which are distinguished in Figures 2a and 2b by roman numerals I to XI.

In addition to the above-mentioned general drive mechanism the following devices illustrated in Figures 2a and 2b and 3 are common to the greater part of the operations and can be conveniently described at this stage:—

A pair of light rails 133 are supported so as 80 to extend throughout the length of the machine above the canisters but nearly touching them. These rails are carried on brackets 134 by means of long studs 135 so that plenty of clear space is allowed around the canisters for the varying operations.

Above the centre of each of the operating stations II to IX inclusive there is a presser foot 136 carried on a vertical spindle 137 which works in a guide 138. The presser foot is best seen in Figure 2b at Station III although similar presser feet can also be seen at all the other stations. The presser feet are operated by levers 139 carried upon a rockshaft 140 which is supported in bearings 141, 142 at the two ends of the machine. The rockshaft 140 is actuated by a rocking lever 143 through a push rod 144. The push rod 144 is connected to the free end of a transverse lever 145 pivoted to a bracket 146 below the bed plate 100. Upon the lever 145 is a cam roll 147 which is operated by a cam 148 on the longitudinal shaft 116 hereinbefore referred to. The presser feet 136 are hung by swinging links 149 from a head block 150, which is slidably mounted upon the plunger 137 and yieldingly connected thereto by a spring 151 bearing on a fixed cover 152. The effect of this arrangement is to ensure that the pressure foot 136 presses evenly along the whole length of the canister and that all the presser feet bear with the same pressure thereon. The cam 148 is so 90

shaped as to depress the presser feet upon the canisters as soon as the chain 118 brings them into operating position at the stations and the presser foot remains pressed upon them during the whole of the time which the chain 118 is at rest and while the folding operations are going on. The rails 133 which overlie the canisters ensure that the canisters shall not be able to rise out of the carriers 117 even when the presser feet are lifted away from them and also, in the event of any gum becoming spread to the outside of the wrapper, the rails 133 ensure that the canister does not rise away from the canister-holder 117 due to sticking of the presser feet 136 when the latter is lifted. Certain auxiliary mechanisms are attached to the presser feet at some of the stations and will be herein-after described.

It will be convenient in describing the remainder of the mechanism to go seriatim through the operations at the successive operating Stations I to XI, but before doing so the actual nature of the folds to be made, as illustrated in Figures 4 and 5, will be described.

In Figures 4 and 5 are shown perspective views of the canister with the wrapper in position thereon and the folds completed. X represents the outer edge of the joint in the wrapper which has been glued to the part of the wrapper underneath and in all cases this glued junction comes at the top of the canister as it goes through the end-folding machine, the canisters with the wrappers upon them and the ends unfolded being laid in this position in the carriers 117 by an attendant. In the machine the first fold which is made consists in turning down the upper part of the projecting ends of the wrappers to form two main folds A and A¹, which, as will be seen, contain the part of the wrapper which is of double thickness. The sides of these folds are creased sharply and then two side folds are turned in, a fold B from one side and a fold C from the other at one end of the canister and two similar folds B¹ and C¹ at the other end of the canister. A bottom fold D or D¹ is then turned up and finally the little intermediate flaps E, E¹ which are created by the making of the main folds are turned in. By end pressure upon the canister the folds are flattened and at the bottom end of the canister, shown in Figure 5, the folds are pressed into the hollow underside of the canister itself.

It will be seen that the effect is to reproduce automatically the exact folds which would be made by an expert hand packer, and, of course, this is done with mechanical regularity.

Referring now to the operations at Station I, the mechanism at this station is illustrated in Figures 6 and 7 and comprises a push rod 153 mounted in a bearing 154 on the bed plate 100 and set at a point such that when the carriers 117 stop at Station I the push rod is co-axial with the canisters in the carriers. The push rod 153 is operated through a link 155 by a lever 156 from a cam 151 on a cam shaft 115. The lever 156 is supported on a bracket 158 and is drawn by a spring 160 so that its cam roll 159 bears against the cam 151. A similar push rod 163 to the rod 153 is located at the opposite end of the canister as can readily be seen in Figure 3b and the two push rods are each operated in a similar way by two cams, one the cam 151 on the shaft 115 and the other a cam 161 on the shaft 116. The rods

advance upon a canister in a carrier 117 simultaneously and their effect is to centre the canister accurately upon the carrier so that it is properly positioned for the subsequent operations.

The details of the mechanism at the second station, where the first or main folds A, A¹ are made, are illustrated as to one side of the machine in Figures 8 to 10. This is the mechanism for making the fold A. The mechanism for making the other main fold A¹ at the other end of the canister is similar and a single description will therefore suffice for both mechanisms. Upon the bed plate 100 there is mounted a bracket 164 which provides a vertical guide 165 for a sliding member 166. The member 166 is secured to a sliding block 167 which has a slot 168 to embrace the cam shaft 115 and which carries on one face a cam roll 169 to engage a cam 170 on the shaft 115. Springs 171, 172 serve to draw the block 167 downwardly and hold the cam roll 169 firmly against the cam 170. Thus the sliding member 166 is periodically moved up and down by the cam 170.

From the sliding member 166 there projects towards the canister near the upper end of the sliding member above the bed plate a bracket 173 which is best seen in the plan, Figure 9, but also appears in dotted lines in Figure 8, and a portion of which can be seen in Figure 10, although in the latter figure the slide 166 upon which it is mounted has been omitted to avoid complicating the drawing. Upon the bracket 173 there is pivotally mounted a swinging carrier 174 for the folding elements or levers 175, 176, which are best seen in Figure 10. The folding levers 175, 176 each carries a smooth brass folding pad 177, 178 to engage the projecting end of the wrapper beyond the canister in the carrier 117 which at the moment of operation happens to lie at Station II, now being described. The pads 177, 178 as the vertical slide 166 carries them downwardly press upon the outstanding upper portion of the paper wrapper and fold it downwardly.

A compound movement is imparted to the pads 177, 178 during this downward movement in order to ensure accurate folding. In the first place the swinging carrier 174 is provided with cam rolls 179, 180 at its upper end which bear upon two fixed cams 181, 182 behind the carrier which are supported upon the bracket 164. The swinging carrier 174 is drawn rearwardly so as to engage these cams by means of springs 183, 184, and the shape of the cams is such that they push the upper end of the carrier 174 forwardly when the slide 166 carries it into its uppermost position. As the pads 177, 178 lie upon the lower ends of the levers 175, 176 and are below the pivot of the carrier 174 the effect is that the pads 177, 178 are retracted in their uppermost position so as to lie somewhat away from the end of the canister, although above the unfolded paper projecting therefrom. As the slide 166 descends the carriers first engage the outside of the paper wrapper at a little distance from the end of the canister and then as they descend they fold the paper inwardly and press it firmly against the end of the canister. Simultaneously the upper ends of the levers 175, 176, which carry cam rolls 185, 186 are pressed inwardly by fixed lateral cams 187, 188 supported on brackets 189 from the vertical guide 165. Thus the pads 177 which begin their downward movement fairly close to one another near the middle of the

outstanding paper which is to be folded downwardly are spread outwardly as they descend, following the circular contour of the rim of the canister on the carrier 117 and they make by 5 this means a broad flat fold which is pressed down closely against the outer surface of the canister. At the conclusion of the downward movement of the pads 177, 178 the carrier 174 is tilted forwardly at its upward end, thus without 10 drawing the pads 178 from the folds which have been made and permitting them to rise with the slide 166 without disturbing the fold. This is effected by a presser 190 which bears on a cam roll 191 carried on a spindle 192 which 15 projects through the cam roll 179 from the carrier 174. The presser 190 is mounted on a slide 193 working in a guide 194 supported on the bed plate 100. The slide 193 is operated by a link 195 from a lever 196 supported on a 20 bracket 197 and carrying a cam roll 198 which co-operates with a cam 199 on the shaft 115. The lever is drawn against the cam 199 by a spring 200.

By the mechanism just described the first or 25 main folds A, A¹ are made and the next operation, carried out at Stations III and IV, is firmly to crease the sides of the main fold thus made.

The apparatus of Station III is shown in 30 transverse vertical section as to one side of the machine in Figure 11, and in plan in Figure 14, which latter figure includes part of Station IV also. Referring to Figure 11 it will be observed that the head block 150 of the presser foot 136 carries pivots 201, 202 for pivoted carriers 203, only one of which is shown in Figure 11. The carriers carry spades 204 which are adapted to press against the folded down portion of the wrapper on the end of the container and hold it in place while the edge of the fold is being creased. The spades 204 are normally held away from the container by a spring 205, but they are pressed in against the ends of the container by a fixed cam 206 which acts on a cam roll 207 35 on an arm 208 on the pivoted carrier 203, so that when the presser foot 136 is depressed at Station III by the descent of the push spindle 137, the spade 204 descends with it and is simultaneously pressed by the cam 206 against the end of the container.

A curved brass backing plate 209, the inner 40 face of which lies just outside the surface of the wrapper when it is held at Station III, on the side thereof nearest to Station II, is provided against which that side of the wrapper may be pressed by a co-operating presser 210 (Figure 14). The backing plate 209 is mounted on a block 211 carried on a plunger 212 which slides in a bearing 213. The plunger 212 is connected by a link 214 to a lever 215 mounted on a bracket 216 and carrying a cam roll 217 for engagement with a cam 218 against which it is drawn by a spring 219. By this means the backing plate 209 is advanced into the position shown in Figure 11 45 ready to back up the wrapper against the pressure of the presser 210 after the carrier 117 has been advanced with the canister as far as Station III and the spades 204 have been pressed against the ends thereof so as to hold the paper firmly in its folded position.

The pressers 210 are mounted on presser levers 220 which are pivoted on the head 211 by means of the screw 221 and the tail ends of which extend in a diagonal direction so as to engage a cam roll 222 (Figure 14). The cam roll 222 is

mounted on a block 223 which is adjustable longitudinally upon a slide 224. The slide is connected by a link 225 to a lever 226 carried on a bracket 227 and having at its lower end a cam roll to engage a cam 228. By the cam 228 presser 210 is pressed against the fold formed on one side of one end of the canister to crease the same sharply and while held in this position the presser 210 and the backing plate 209 are withdrawn together by the action of the cam 218 80 away from the canister.

At Station IV a precisely similar mechanism comprising a backing plate 229 and a presser 230 serves in the same way to crease the other side of the main fold. It is not necessary to describe this second mechanism again in detail but it is sufficient to point out that the plunger 231 corresponds to the plunger 212 and is operated by a lever 232 corresponding to the lever 215, while the presser 230 is operated by a lever 233 corresponding to the lever 220 through the action of a cam roll 234 on a slide 235 operated by a cam-actuated lever 236.

At Station IV, moreover, the first side crease B is folded in from that side of the first fold 100 which was creased at Station III. This is effected by a brass folder 237 which first engages the upper part of the outside of the creased fold and moves downwardly and inwardly into the position shown in Figures 13 and 14 pressing the 105 side fold before it. In order to impart these movements to the folder 237 it is mounted on a folding-lever 238 which is pivoted on a horizontally sliding element 239 working in a horizontal slide 240. The horizontal slide 240 is mounted to 110 move on a vertical slide 241 carried in a guide bracket 242. On one side of the guide bracket 242 there is a fixed cam 243 which engages a cam roll 244 on the horizontally sliding element 239. A spring 245 serves to draw the element 239 115 in such a direction as to hold its cam roll 244 against the cam 243. The horizontal slide 240 carries a fixed cam 246 against which bears a cam roll 247 on the tail of the lever 238. Thus vertical movement of the slide 241 will cause a 120 corresponding horizontal movement of the sliding element 239 and this in turn will cause a movement in and out towards the canister of the lever 238 due to the tail of this lever working upon the contour of the cam 246. The folder 125 237 will therefore move in a predetermined three-dimensional path sweeping downwardly and inwardly from a position outside the wrapper at Station IV into the position shown in Figures 13 and 14. This folding movement of 130 the folder 237 is derived from a cam 248 on the shaft 115, which cam engages a cam roll 249 on a vertically sliding block 250 secured to the vertical slide 241. The block 250 is drawn downwardly against the cam 248 by springs 251. The 135 shape of the cam 243 can best be seen in Figure 2b.

At station V, which is illustrated in Figures 15 and 16 in detail, there is a folder 252 mounted on a lever 253 which operates to fold the second 140 side crease of the canister, namely the crease C, and this operates in exactly the same way as the folding mechanism of the folder 237 just described for Station IV, but is all made left-handed as compared with that mechanism. 145 It is not necessary to describe this mechanism in detail save to observe that the lever 253 corresponds to the lever 238, that it is mounted on a horizontally sliding element 254 corresponding to 239 and that the latter is carried on 150

a vertical slide 255 corresponding to 244. In addition to these parts, at Station V, there is a presser 256 the object of which is to flatten the edges of the fold B which was made at Station IV. This presser 256 is mounted on a sliding shank 257 in a carrier head 258. The sliding shank is drawn downwardly relatively to the carrier head by a spring 259 and the carrier head is mounted on a sliding bar 260. The bar 260 slides in a guide 261 and is actuated by a lever 262 through a connecting rod 263 from a cam lever 264 which carries a cam roll 265 and is actuated by a cam 266 on the shaft 116. A spring 267 draws the lever 264 downwardly towards the cam 266. It will be understood that the carrier head 258 is symmetrical about the sliding rod 260 and that it carries a presser foot similar to 256 adjacent to the other end of the canister on the carrier 117 and thus that these two pressers for flattening the folds A are both actuated simultaneously although only one of them, operating on one end of the canister, is shown in Figures 15 and 16.

25. Station VI (Figures 17 and 18) is provided with a further folding mechanism comprising a guide bracket 270 in which works a vertical slide 268 carrying a horizontal slide 269. In the horizontal slide 269 works a horizontally sliding member 271 on which is pivoted a horizontal lever 272 carrying a folder 273. There is a fixed cam 274 on the side of the bracket 270 and the mechanism is operated from a cam 275 on the shaft 115. The mechanism as a whole is a duplicate of that provided for the folder 252 at Station V but the shapes of the cams differ slightly as can be seen from Figure 18 and the shape of the presser is such as to cause it to move a little lower down across the face of the folds on the canister and thus to increase the side fold C more closely to the bottom fold D and ensure that the latter is ready for the next operation at Station VII.

45. At Station VII the bottom fold D at the end of the canister is flattened between a support 276 (Figure 19) and a presser foot 277. The presser foot 277 is mounted in a carrier head 278 on a sliding plunger 279, and as in the case of the carrier head 258 at Station V, the head carries elements for dealing with both ends of the canister simultaneously.

50. The presser foot is provided with a spring 280 (shown in Figure 2a) which affords a yielding connection between it and the carrier head.

55. The plunger 279 slides in a bearing 281 and is operated by a rocking lever 282 which itself is actuated by a connecting rod 283 from a cam lever 284 below the bed plate 100. The cam lever carries a cam roll 285 and is operated by a cam 286 on the shaft 116. Thus, after the canister at Station VII has been held firmly down by the descent of the appropriate presser foot 136 the plunger 279 descends and forces the presser 277, which overlies the bottom fold D, downwardly against the support or tablet 276 which underlies this fold. In order to ensure that the tablet 276 is not in the way of the forward movements of the canisters into position at the station and that it never overrides any of the bottom folds D, even though these may not all be lying at a perfectly regular angle, the tablet 276 is arranged to be depressed except at such times as it is required to engage the bottom fold D. To this end it is mounted on

a sliding plunger 287 mounted in a bearing 288 below the bed plate 100 and the plunger is lifted at appropriate times by a link 289 which connects it with a cam lever 290 carrying a cam roll 291 co-operating with a cam 292 on the shaft 80 115. The levers 284 and 290 are drawn downwardly against their respective cams by springs 293 and 294.

85. At Station VIII the bottom fold D, which has been flattened by the presser foot 277 at Station VII, is folded upwardly flat against the end face of the canister and the small lower intermediate flaps E, E are flattened as a preliminary to folding them in against the ends of the canister at Station IX. This mechanism is shown in detail in Figures 21 to 23 and will now be described.

90. Referring first to Figure 21, upon the head 150 of the presser foot 136 at this station there is pivoted a carrier 295 for a spade or holder 296. There is a spade 296 for each end of the canister and they are both mounted upon the head 150, but only one of them is shown in Figure 21. The carrier 295 is pivoted to the head 150 and carries a cam lever 297 which projects upwardly from it and has a cam roll 298 at its upper end. A fixed cam 299 is mounted on the bearing of the plunger 137 and engages the cam roll 298, which is drawn against the cam by a spring 300. Thus, as the presser foot 136 is pressed down by the plunger 137 the spade 296, which initially stands out well away from the ends of the canister, is carried downwardly and simultaneously moved inwards by the action of cam 299 until it presses upon the end of the canister 100 as shown in Figure 21. The shape of the spade 296 can best be seen in Figure 23 and it will be seen that it conforms to the outline of the canister and that it will lie below and not interfere with the upper pair of the small intermediate flaps E, E. The purpose of the spades 296 is to hold the canister and the upper part 115 of the flaps which have been folded down over its ends firmly during the operation of folding the bottom flap D upwards.

105. Coming to the mechanism for performing the latter operation, this is operated from below the bed plate 100 and the main element therein is a folder 301 (Figures 21 and 23) which is pivoted at 302 on a forwardly projecting lug 120 125 303 supported by a vertical slide 304 which works in a guide 305. The folder 301 is of somewhat complicated shape which can best be seen in Figure 23 and it extends below the pivot 302 to a point at which it carries a cam roll 306 and 130 an attachment 307 for a spring 308 which draws the lower part of the folder 301 towards the slide 304 and thus presses the upper part yielding against the end of the canister. The cam roll 307 works on a cam 309 which is fixed on 135 the side of the guide 305. The shape of the cam 309 is such as to maintain the folder 301 in a plane nearly coincident with the plane of the end of the canister during the course of its movement from a position below the bottom fold 140 D up to a position such as is shown in Figure 21. In this position the bottom flap has been folded by the folder 301 closely against the end of the canister. Further vertical movement, however, withdraws the folder 301 from immediate contact with the end of the canister so as to leave the flap D free of constraint while the lower intermediate flaps E are being flattened as will be hereinafter described.

145. The vertical movement of the folder 301 is 150

accomplished by moving the slide 304 upwards and this is effected by a cam 310 on the shaft 115 which engages with a cam roll 311 on a slide block 312 which is forked to engage the shaft 115 and is secured at its upper end to the slide 304. The slide 312 is drawn downwardly against the cam 310 by means of two springs 313, 314.

The folder 301 just above the pivot 302 by which it is secured to the lug 303 is broadened out laterally to form a bearing plate 315 on which are pivoted two intermediate-flap flattening-levers 316, 317. The intermediate-flap flattening-levers carry flattening-pallets 318, 319 at their upper ends, and below their pivots on the plate 315, at their bottom ends they carry cam rolls 320, 321 which co-operate with fixed cams 322, 323 projecting forwardly from the sides of the guide bracket 305. Springs 324, 325 serve to maintain the cam rolls 320, 321 in engagement with the cams 322, 323. As will be observed in Figure 23 the cams are somewhat widely spaced apart over all the lower part of their contour, allowing the cam rolls 320, 321 to move apart from one another and the pallets 318, 319 at the upper ends of the flattening-levers to be close together. At the upper portions of the cam contours, however, they approach one another rapidly and thus during upward movement of the slide 304, just as this reaches the top of its stroke, the bottom ends of the flattening levers are brought rapidly together against the action of the springs 324, 325 and the upper ends are moved outwardly to the position shown in Figure 23. This sudden outward movement of the flattening-levers occurs after the folder 301 has folded up the bottom flap D and at a time when the cam roll 306 has withdrawn the folder 301 from direct contact with the end of the canister. Consequently, the flap is free and the little intermediate flaps E which are formed at its bottom corners can be pressed by the pallets 318, 319 firmly and flatly against supports 326, 327 which underlie these intermediate flaps. The supports 326, 327 form part of a yoke 328 which is screwed to the back of the folder 301 and therefore they move up into position beneath the intermediate flaps just as the pallets are brought down upon them. Moreover, owing to the action of the cam 309 in tipping the presser 301 away from the canister at this stage of the operations, the pallets 318, 319, while gripping the little intermediate flaps E against the supports 326, 327, are drawn away from the canister and therefore have a sliding movement over these intermediate flaps which assists in creasing them sharply and making sure they are well flattened. The upper intermediate flaps above the spade 296 are not affected by these operations but they do not need flattening to the same extent as they are formed by a different folding operation from that which produces the lower flaps. In the creasing of the lower intermediate flaps E the canister is released and moved to Station IX.

At Station IX the upper and lower small intermediate flaps E are all four of them turned inwardly at both ends of the canister and this completes the actual folding operations in the machine. The mechanism is illustrated in Figures 24, 25 and 26. Two independent mechanisms are provided, one for turning down the top intermediate flaps and the other for turning up the bottom intermediate flaps. Beginning with

the former this is actuated by a cam 329 on the shaft 115 which engages a cam roll (shown dotted in Figure 24) 330 and a cam lever 331. Lever 331 is pivoted at its centre to a bracket 332 on the underside of the bed plate 100, and its outer end is linked by a connecting rod 333 to a rocking lever 334 pivoted at 335 to a bracket 336 above the bed plate. A spring 337 serves to lift the connecting rod 333 and thus to hold the cam roll of the lever 331 firmly against the cam 329. This spring is assisted in its action by a second spring 338 acting directly upon the lever 334. The inner end of the latter is connected by a link 339 to a vertical slide 340 in a guide bracket 341 secured to the upper side of the bed plate 100 opposite the canister at Station IX. Some of these parts are shown in elevation as viewed from the inner side of the machine in Figure 25. The slide 340 carries a crosshead 342 which works immediately behind a guide plate 343 supported by brackets 344, 345 on the bed plate 100. The guide plate 343 is slotted obliquely on the side nearest to the cross-head 342 to receive two upper intermediate folding-plungers 346, 347. The plungers 346, 347, 100 which are rectangular in cross-section carry cam rolls 348, 349 (shown dotted in Figure 25) and the cam rolls enter horizontal slots 350, 351 in the crosshead 342. Thus, when the slide 340 is depressed by the cam 329 the folding plungers 346, 347 will be moved in an oblique line downwardly. They carry at their lower ends hinged folders 352, 353, the shape of which is best seen in Figure 26. The folders 352, 353 have tail pieces 354 which are drawn up by springs 355 110 so that the folders normally stick out at right angles to the folding plungers 346, 347 as shown in Figure 26. The underside of the folders has a downward projection 356 to engage the back or upper side of the intermediate flaps E. As 115 the plungers 346, 347 are depressed the folders 352, 353 engage the flaps by means of their downward projections 356 and bend them downwardly.

On further movement of the parts below the 120 position shown in Figure 26, the forward edges of the folders 352, 353 are held against further downward movement by the edge of the canister and in consequence the springs 355 are extended and the folders 352, 353 canted about the edge 125 of the canister and so press the intermediate flaps E firmly against the ends of the canister.

The means for folding the lower intermediate flaps E upwardly comprise a cam 357 (Figure 24) mounted upon the shaft 115 and engaging a cam roll 358 on a folding slide block 359 secured to the lower end of a vertical sliding member 360. The sliding member 360 works in the bottom part of the same guide 341 as that which supports the upper slide 340. The vertical sliding element 360 carries two cam rolls 361, 362 near its upper end and these underlie two pivoted fingers 363, 364. The fingers 363, 364 are pivoted at 365, 366 respectively (see Figure 25) on two trunnions 367, 368 which are themselves mounted 130 to turn in bearings in the brackets 344, 345. Thus the fingers 363, 364 are in effect mounted on universal joints and can move in any direction. The upward movement of the cam rolls 361, 362 brings them nearer together. Their 145 rear faces are formed as cam faces 369 and are adapted to engage inclined cam rolls 370 (see Figure 26) by which as they are moved inwardly by the upward movement of the slide 360 they are simultaneously caused to approach the end 150

of the canister. Hinged upon the front faces of the fingers 363, 364 are brass folders 371, 372 the shape of one of which can best be seen in Figure 26. The folders 371, 372 have pallets or faces which engage the lower intermediate flaps and turn them upwardly and press them against the end of the canister under the above described movement of the fingers 363, 364. It will be appreciated that the fingers 363, 364 are held against the two sets of cam rolls by springs 373, 374 operating in one direction and 375, 376 operating in the other direction. Thus, the lower small intermediate flaps E are folded upwardly.

While this has been going on a third operation has been performed upon the folded flaps where they overlap one another in the centre of the canister. Pressure is applied to these flaps by a sliding iron 377 to flatten them upon one another. The iron 377 is formed on the end of a cross-slide 378 which is mounted between a bracket 379 on the slide 360 and a cover plate 380 which is screwed to the bracket 379 with distance pieces 381 interposed so as to allow free movement of the slide 378. The slide 378 extends right through the vertical side 360 in which it finds an additional bearing surface to support it and it carries at its rear end a cam roll 382 which works against a cam 383 shown in chain line in Figure 26 but seen fully in Figure 24. The shape of the cam 383 is such as to hold the iron 377 away from the end of the canister in the lower part of the movement of the slide 360 but to allow it to approach the canister in an oblique direction during upward movement of the slide and thereafter to effect a sliding movement over the end of the canister to flatten the folds. Pressure is exerted during this sliding movement by a spring 384.

After the operations just described the canister is moved forward to Station X, the mechanism of which is illustrated in Figures 27 and 28. Here the now completed end folds are subjected to pressure between plungers 385, 386. The plunger 385 is faced with rubber so as to allow some resiliency and avoid damaging the canisters in the event of slight variation of size. The plungers 385, 386 are mounted on sliding bars 387, 388 and only the operating mechanism of one bar is illustrated, that of the other being similar. The bar 387 slides in a bearing 388 on the upper side of the bed plate 100 and is connected by a link 389 to a cam lever 390 which is supported in a bracket 391 and carries a cam roll 392 to engage a cam 393 on the cam shaft 115. A spring 394 holds the cam roll 392 against the cam 393. By this means the folds are firmly pressed against the ends of the canister and made to conform to the shape thereof. The bottom of the canister is slightly hollowed as is usual with any tin canisters, and consequently the plunger 386 is shaped to enter the hollow bottom of the canister and to force the folds thereinto. On the other hand at the lid end of the canister the plunger 385 is flat and merely serves to press the folds on to the lid closely.

On being released from Station X the canister has the appearance illustrated at Station XI in Figure 2a and in greater detail in Figures 4 and 5.

At Station XI, shown in Figure 29, the canister is automatically removed from the travelling carrier 117 by a rotating paddle 395 mounted

on a shaft 396 and driven by spur gear 397, 398 from a chain 399 operated by a sprocket on the bracket 391, see Figure 2a. Above the rotating paddle 395 is a sheet iron guide 400 which keeps the canister in engagement with the paddle 395 while it sweeps over the top arc of its revolution about the axis of the shaft 396 and delivers the canister clear of the end of the machine on to a conveyor belt not shown in the drawings. By this means the canisters are automatically removed from the machine as fast as they are packed and may be carried to a packing room where they are put into cases or boxes.

Figure 30 shows a modification which can be employed at Stations III to VI inclusive for creasing and making the lateral folds B and C. The figure is a plan view and shows at Station III a creasing mechanism for the side-fold B, at Station IV a similar mechanism reversed for creasing the main fold for the side-fold C and at Stations V and VI mechanism for making folds B and C themselves. Upon the bed plate 100 there is mounted a guide 401 for a horizontal cross plunger 402. The plunger 402 is connected to a cam lever 403 which is operated by a cam on the shaft 115 as already described and as will be readily understood. The plunger 402 carries a crosshead 404 in which is mounted an outside presser 405 and an inside presser 406. Both these pressers can slide in the crosshead 404 transversely to the direction of advance of the plunger 402. The outside presser 405 carries a cam roll 407 which works in a fixed cam slot 408. The inside presser 406 carries a cam roll 409 which works against a cam 410. The cam 410 is mounted on a sliding plunger 411 supported in a guide 412 and operated by a crosshead 413 connected to a cam lever 414. When the plunger 402 is first advanced the cam 410 is withdrawn and the inside presser 406 lies well clear of the outside presser 405. The outside presser 405 in its initial position before advance of the plunger 402 lies well outside the line of the fold of the wrapper with which it is to be engaged. Thus, on advance of the plunger 402 the outside presser 405 advances upon the outside of the fold of the wrapper with an oblique movement. Thereafter the cam 410 is advanced and the underside 125 presser 406 is moved transversely to engage the underside of the fold of the wrapper and to press it firmly against the outside presser 405. Thereafter the parts are withdrawn leaving the fold sharply creased. At Station IV the 130 left-hand side of the fold is creased in a similar way by an outside presser 415 and an inside presser 416. Both these are provided with cams as already described and the movable cam 417 of the inside presser is connected by a plunger 135 418 to the same crosshead 413 as that which operates the inside presser 406. This simplifies the mechanism.

At Stations V and VI the creased sides of the first flap are folded inwardly to make the side flaps B and C by means of pivoted folders 419, 420. These are mounted on brackets 421, 422 on a vertical slide 423 and they carry crank arms 424, 425 which project on opposite sides of their pivots and are connected by a crossed connecting rod 426. The crossed connecting rod ensures that clockwise movement of the folder 419 is accompanied by anti-clockwise movement of the folder 420 and as the pivots of the two folders lie one to the left and the other to

the right of their respective folding stations one will make a left-handed fold at the same time that the other makes a right-handed fold and with a single movement of the connecting rod 426. The connecting rod 426 carries a cam roll 427 which bears against a long vertical cam roll 428 on a bell crank lever 429 pivoted on the bed plate 100. The bell crank lever is operated by a link 430 through a universal joint member 431 from a cam lever 432, operated as before by a cam on the shaft 115. The vertical slide 423 is operated by another cam on the shaft 115. The cam roll 427 is kept pressing against the long vertical cam roll 428 in all positions of the cam slide 423 by a spring 433. In the initial position of the parts before folding the cam roll 428 of the bell crank lever 429 is swung over to the right as viewed in Figure 30 and the spring 433 is contracted, the folders 419, 420 being approximately at right angle to the position in which they are shown in the drawings and the slide 423 being at the uppermost limit of its travel. As the slide 423 descends the bell crank lever 429 is pushed over and the folders move towards the position shown in the drawings with an oblique downward and inward sweep which ends with the bottom of the folders just above the bottom flap D and with their working faces or pallets pressed firmly against the ends of the canisters. Subsequent operations of folding are performed as already described.

I claim:—

1. In a canister wrapping machine wherein the wrapper is rolled around the canister, the provision of means for end-folding the wrapper, comprising in combination a vertically reciprocable carriage, fingers mounted upon said carriage so as to be movable therewith in a plane parallel to and close to the end of the canister above the projecting end of the wrapper therefrom, said fingers being movable relatively to the carriage transversely to the vertical movement thereof and being cam-actuated to follow the contour of the end of the canister to fold down a part of the projecting end of the wrapper to form a main fold, and means for sharply creasing the still outstanding doubled over side folds formed by turning down the main fold which comprise a backing plate and a presser mounted to engage the exterior and interior of the side fold respectively, means for pressing them together and means for retracting them from the side fold thereafter.
2. Automatic apparatus for wrapping canisters comprising in combination means for encircling the canister with a sheet of wrapping material exceeding in width the length of the canister and in length the periphery of the canister, the latter being positioned intermediate the ends of the encircling sheet and the edges of the sheet overlapping one another along the canister, means for adhesively attaching to one another the said overlapping edges of the encircling sheet and means for folding over the projecting ends of the encircling sheet towards the ends of the canisters and pressing the folded-over ends in stiff creases against the ends of the canister, in the form of one main fold and two side folds, and means for flattening a bottom flap left outstanding as a result of the folding in of said main and side folds, comprising a support and a top presser foot cam-actuated to press upon one another after a canister has been positioned to hold the fold be-
3. In a canister wrapping machine wherein the wrapper is rolled around the canister, the provision of means for end-folding the wrapper, comprising in combination a vertically reciprocable carriage, fingers mounted upon said carriage so as to be movable therewith in a plane parallel to and close to the end of the canister above the projecting end of the wrapper therefrom, said fingers being movable relatively to the carriage transversely to the vertical movement thereof and being cam-actuated to follow the contour of the end of the canister to turn down a part of the wrapper to form a main fold, means for sharply creasing the outstanding doubled side folds formed by turning down said main fold, means for folding in said creased side folds, and means for flattening a bottom fold left outstanding, as a result of the folding in of said side folds comprising a support and a top presser foot cam-actuated to press upon one another after the canister has been positioned to hold the fold between them, one of these elements being operated through yielding means for the purpose described.
4. Automatic apparatus for wrapping canisters comprising in combination means for encircling the canister with a sheet of wrapping material exceeding in width the length of the canister and in length the periphery of the canister, the latter being positioned intermediate the ends of the encircling sheet and the edges of the sheet overlapping one another along the canister, means for adhesively attaching to one another the said overlapping edges of the encircling sheet and means for folding over the projecting ends of the encircling sheet towards the ends of the canister in a series of overlapping folds and means for sharply creasing the wrapper, where it becomes doubled upon itself by the formation of one fold, prior to the folding in of said doubled part to form a succeeding fold.
5. Automatic apparatus for folding in projecting ends of wrappers of greater width than the length of the canisters which they encircle comprising in combination a step-by-step conveyor having carriers for receiving the canisters and a series of stations at which the canisters are presented at rest by the conveyor and at which a series of folding and creasing means, operated alternately, are provided for folding in the projecting ends of the wrappers in a series of overlapping folds, wherein the conveyor is provided with carriers shaped to receive the canisters while permitting their axial movement and reciprocating plungers are provided at the first station for centering the canister with the wrappers thereon relatively to the folding means and a downwardly pressing plunger is provided at some of the stations for bearing on the canister and maintaining it in position in the carrier during the period of rest at the station.
6. Automatic apparatus for folding in the projecting ends of wrappers of greater width than the length of the canisters which they encircle, comprising in combination a step-by-step conveyor for presenting the canisters at a series of stations, means at the first station for centering the canister with the wrapper thereon and

means at a succeeding station for forming main folds simultaneously at each end of the canister comprising fingers reciprocable towards and away from the partly wrapped canister in such a direction as to press portions of the projecting ends of the wrapper in the form of folds which lie against the ends of the canister, and means at further stations for sharply creasing the parts of the wrapper where it becomes doubled upon itself as a result of the formation of said main folds, comprising backing plates and pressers mounted to engage the exterior and interior of the said projecting parts of the wrapper respectively, means for pressing them together and means for retracting them from the side fold thereafter.

7. Automatic apparatus for folding in the projecting ends of wrappers of greater width than the length of the canisters which they encircle comprising in combination a step-by-step conveyor for presenting the canisters at a series of stations, means at the first station for centering the canister with the wrapper thereon and means at a succeeding station for forming main folds simultaneously at each end of the canister comprising fingers reciprocable towards and away from the partly wrapped canister in such a direction as to press portions of the projecting ends of the wrapper in the form of folds which lie against the ends of the canister, means at further stations for sharply creasing the parts of the wrapper where it becomes doubled upon itself as a result of the formation of said main folds, comprising backing plates and pressers mounted to engage the exterior and interior of the said projecting parts of the wrapper respectively, means for pressing them together and means for retracting them from the side fold thereafter, together with a spade for engaging each end of the canister and holding the main folds from movement during the side creasing operation.

8. Automatic apparatus for folding in the projecting ends of wrappers of greater width than the length of the canisters which they encircle, comprising in combination a step-by-step conveyor for presenting canisters at rest at a series of stations, reciprocating plungers at the first station for centering the canister with the wrapper thereon, means at the second station for forming a main fold, means at the third station for sharply creasing the doubled parts of the wrapper still outstanding, and means at a subsequent station for turning in a creased part to form a side fold comprising a presser mounted upon a vertical slide so as to be capable of a sliding movement and so cam-controlled as to move across the face of the canister from the outside of the fold at the side thereof in a direction slanting downwards towards the center of the bottom flap thereof.

9. In automatic apparatus as claimed in claim

8 the provision of means for flattening the bottom flap formed as a result of the folding in of the side flaps comprising a support and a top presser foot cam-actuated to press upon one another after a canister has been positioned to hold the fold between them, one of these elements being operated through yielding means for the purpose described.

10. In automatic apparatus for folding in the projecting ends of wrappers of greater width than the length of the canisters which they encircle having a step-by-step conveyor for presenting canisters at a series of stations and means at said stations for folding in a series of overlapping folds and means operating alternately with said folding means for sharply creasing the outstanding parts of the wrapper where it becomes doubled upon itself following the folding in of a fold, the provision of means for folding in intermediate flaps comprising pivoted flap-turning members movably mounted so as to move substantially radially inwards across the ends of the canister at the points where the said flap projects.

11. In automatic apparatus, for folding in the ends of wrappers of greater width than the length of the canisters which they encircle, having a step-by-step conveyor for presenting canisters at a series of stations and means at said stations for folding in a main fold, two side 105 folds, a bottom fold and four small intermediate folds and means operating alternately with the folding means for creasing doubled parts of the wrapper prior to the folding in of said parts, the provision of pressers for engaging the ends of 110 the canisters and flattening the completed overlapping folds against the ends of the canisters.

12. Automatic apparatus for folding in the projecting ends of a wrapper of greater width than the length of a circular canister which it 115 encircles, comprising in combination a main frame, and arranged at a series of stations thereon means for folding down part of the projecting end of the wrapper to form a main fold, means for sharply creasing the still outstanding doubled parts, means for folding in the creased parts to form two side folds overlapping said main fold and leaving a bottom flap still outstanding, means for sharply creasing the doubled edges of said bottom flap, means for 125 folding up said bottom flap to form a fold partly overlapping said side folds and leaving intermediate flaps still outstanding means for sharply creasing the doubled edges of said intermediate flaps, means for folding in said intermediate flaps, together with a step by step conveyor for conveying the encircled canisters and presenting them at rest at the stations aforesaid whereby the projecting end of the wrapper is folded in a series of overlapping 130 folds.

WILLIAM HENRY WALL.
